Primary Examiner — Mitchell Siegel*(74) Attorney, Agent, or Firm* — Terence P. O'Brien(57) CLAIM

We claim the ornamental design for a tennis racquet, as shown and described.

DESCRIPTION

FIG. 1 is a front, side perspective view of a tennis racquet; FIG. 2 is a front view of the tennis racquet of FIG. 1; FIG. 3 is a side view of the tennis racquet of FIG. 1; FIG. 4 is a top view of the tennis racquet of FIG. 1; FIG. 5 is a bottom view of the tennis racquet of FIG. 1; and, FIG. 6 is a cross sectional view taken on line 6-6 of FIG. 2. The ornamental design that is claimed is shown in solid lines in the drawings. The broken (dashed) lines shown in FIGS. 1 through 6 are included for the purpose of illustrating environmental elements only and form no part of the claimed design.
